UNITED STATES PATENT OFFICE

BYRON F. HANNUM, OF CLEVELAND, OHIO, ASSIGNOR TO HUNT & DORMAN MANUFACTURING COMPANY, OF CLEVELAND, OHIO, A CORPORATION OF OHIO

FIREPROOF FILING CONTAINER

Application filed October 16, 1929. Serial No. 399,988.

This invention relates to fireproof filing cabinets for storing such combustible and explosive objects as nitro-cellulose X-ray films and the like, and the general purpose of this invention is to provide a safe and convenient means for storing such films and the like.

Another object of this invention is to allow sufficient means of escape for gases generated by the burning films to prevent the explosion thereof under all circumstances; another object of this invention is to limit, in case of fire, the combustion to one container of the filing cabinet so that the destruction of the contents of one container will not in any way destroy the contents of the adjacent containers.

Still another object of my invention is to prevent water or any liquid dropping on to one of these compartments either from a sprinkling means or from any source, from entering into a compartment and damaging the contents therein.

Another object is to provide a readily closable cover which will be quickly and automatically closed when a container is inserted in the rack, while another object is to provide a suitable means for holding the cover in open position while the contents of the container are accessible.

In the drawings accompanying this specification and forming a part of this application, I have shown, for the purposes of illustration, one form which my invention may assume, and in these drawings:

Fig. 1 is a central vertical section from front to rear taken substantially on the line 1—1 of Fig. 2;

Fig. 2 is a central vertical section at right angles to Fig. 1, taken on the line 2—2 of Fig. 1;

Fig. 3 is a horizontal section on the line 3—3 of Fig. 1, while

Fig. 4 is a fragmentary vertical section showing the container pulled out and the cover opened.

I show the embodiment of my invention as applied to an all metal container 11 having two sides 12 joined by a front 13, a back 14 and a bottom 15. Any suitable means may

be used for constructing this container, the embodiment herein shown however consisting of a container having the various parts welded together thus providing a strong and waterproof construction. A plurality of small apertures 16 are disposed near the top of the two sides 12 for permitting the ready escape of any gases formed within the container 11, while a cover 17, also of an all-metal construction, is provided with flanges 18 extending below the apertures 16 when the cover 17 is in closed position on the container 11. The flanges 18 are constructed so that they are spaced a short distance from the sides 12 of the container 11 for permitting the free passage of gases from the inside of the container 11 through the apertures 16. The cover 17 is secured to the top of the back 14 of the container 11 by means of a hinge 19 suitably secured to the inner surface of the flange at the rear of the cover 17 and to the top and outside surface of the back 14. A convenient handle 20 suitably secured to the outside surface of the front 13 of the container 11 provides a convenient means for moving the container 11, while a label-holder 21 suitably secured to the outside surface of the front 13 provides a convenient means for marking or indexing the contents of the container.

It usually will be found desirable to use a plurality of these containers, and when more than one of such containers is used, it is found desirable to use a rack 22 herein shown as comprising spaced vertical T-irons 23 joined by horizontally disposed angle irons 24 secured thereto by any suitable means, and support angle irons 26 resting on the horizontal angle irons 24 are secured thereto in any suitable manner as by welding and these support angle irons 26 provide a track means for permitting the sliding of the container 11 in the rack 22. The support angle irons 26 are depressed downwardly and flared outwardly, intermediate their ends, as indicated at 35, for deflecting liquid onto the container below. The vertical T-irons 23 at the front of the rack 22 are provided with notches 27 adapted to cooperate with a horizontally disposed retaining bar 28 suitably disposed on the outside surface of the back 14 of the con-

tainer 11 and extending shortly beyond the sides thereof, the same being secured to the back 14 of the container 11 by clips 29 secured to the back 14 in any suitable manner. 5 A loop 30 having one end secured in a clip 31 suitably secured to the outside of the flange at the back of the cover 17 cooperates with a corrugated clip 32 suitably secured to the outside of the back 14 for holding the 10 cover 17 in a fixed open position over the container 11.

In actual operation, it will be found advisable to line the bottom of the container 11 with a fireproof and heat resisting material herein shown as a strip of asbestos 33 so that films contained therein will be protected from the flame and heat which might be generated in an adjacent container. 15

In operation the operator first takes hold 20 of the handle 20 and slides the container 11 forwardly until the retaining bar 28 rests against the vertical T-irons 23 and when the container 11 has reached this position, it will be held in an advanced position by means of 25 the retaining bar 28 resting against the vertical T-irons 23. The cover 17 then is opened by lifting up the front of the cover, the same swinging freely on the hinge 19 until the loop 30 engages one of the corrugations in the clip 32 at which time the cover will be held in an 30 open position as illustrated in Fig. 4. The container 11 now is in position for the inserting and removing of films. In the event that the films in the container 11 should be 35 ignited while the container is in an advanced position with the cover 17 open, the operator may quickly and easily limit the flames produced by such ignition to this one compartment by sliding the container 11 quickly back into position in the rack 22 and as soon as the 40 top 17 engages the horizontal angle iron immediately above, it will release the loop 30 from its position in the clip 32 and thereby permit the cover to close by gravity. When the cover 17 is thus returned to the rack, sufficient 45 means of escape are given for the gases generated therein to prevent the explosion of any other films within said container and the flames are confined to the one container. If such rack supporting the containers 50 11 is in a room provided with an automatic sprinkling system, the heat from the flame will cause the sprinkling system to drop a spray of water on the containers. It will be apparent that the flanges 18 on the 55 cover 17 will prevent any dripping water from entering the container 11.

From the foregoing, it will be apparent to those skilled in the art that a readily accessible all metal container has been provided 60 which will prevent the explosion of films therein and at the same time protect the contents from water or any liquid which might be dropped thereon for the purpose of extinguishing a flame. It further will be apparent 65 to those skilled in the art that the invention

possesses uses and advantages not specifically mentioned herein and that the invention may be variously changed, used and modified, all without departing from the spirit of the invention or sacrificing the advantages thereof, and it therefore will be understood that the disclosure herein is illustrative only and that the invention is not limited thereto. 70

Having thus described my invention, what I claim is:

1. A fireproof container, as for storing such combustible and explosive articles as films and the like, comprising: a rectangular fireproof container provided with apertures along its sides for permitting the escape of gases therefrom; a cover means secured by hinges to one side of said container; and flanges on said cover means extending over said apertures, for preventing dripping liquid from entering said apertures, and spaced from said container for permitting gases to escape from said container through said apertures. 80

2. A fireproof container, as for storing such combustible and explosive articles as films and the like comprising: a rectangular fireproof container provided with apertures along its sides for permitting the escape of gases therefrom; a cover means secured by hinges to one side of said container; means for holding said cover in adjustable fixed position over said container; and flanges on said cover means extending over said apertures, for preventing dripping liquid from entering said apertures, and spaced from said container for permitting gases to escape from said container through said apertures. 90

3. A fireproof container, as for storing such combustible and explosive articles as films and the like comprising: a fireproof container provided with apertures along its sides for permitting the escape of gases therefrom; a cover means for said container; a clip on said cover; a corrugated clip on one side of said container; a loop cooperating with both said clips for holding said cover in adjustable fixed position over said container; and flanges on said cover means extending over said apertures, for preventing dripping liquid from entering said apertures, and spaced from said container for permitting gases to escape from said container through said apertures. 100

4. A fireproof filing cabinet, as for storing such combustible and explosive articles as films and the like comprising: a fireproof container provided with apertures along its sides for permitting the escape of gases therefrom; a rack for supporting said container and permitting said container to slide therealong; a support bar mounted on said container adapted to cooperate with the front of said rack for supporting said container in fixed predetermined advanced position substantially out of said rack; a cover means for said container; and flanges on said cover 110

means extending over said apertures, for preventing dripping liquid from entering said apertures, and spaced from said container for permitting gases to escape from said container through said apertures.

5. A fireproof filing cabinet, as for storing such combustible and explosive articles as films and the like comprising: a fireproof container provided with apertures along its sides for permitting the escape of gases therefrom; a rack for supporting said container and permitting said container to slide therewith; a cover means for said container; hinge means cooperating with said cover means and said container for permitting the swinging of said cover means on said container; means for closing said cover means as said container is being inserted in said rack; and flanges on said cover means extending over said apertures, for preventing dripping liquid from entering said apertures, and spaced from said container for permitting gases to escape from said container through said apertures.

25 6. A fireproof filing cabinet, as for storing such combustible and explosive articles as films and the like comprising: a fireproof container provided with apertures along its sides for permitting the escape of gases therefrom; a rack for supporting said container and permitting said container to slide therewith; a cover means for said container; hinge means cooperating with said cover means and said container for permitting the swinging of said cover means on said container; cam means on said rack for closing said cover means as said container is being inserted in said rack; and flanges on said cover means extending over said apertures, for preventing dripping liquid from entering said apertures, and spaced from said container for permitting gases to escape from said container through said apertures.

45 7. A fireproof filing cabinet, as for storing such combustible and explosive articles as films and the like comprising: a fireproof container provided with apertures along its sides for permitting the escape of gases therefrom; a rack for supporting said container and permitting said container to slide therewith; a support bar mounted on said container adapted to cooperate with the front of said rack for supporting said container in fixed predetermined advanced position substantially out of said rack; a cover means for said container; hinge means cooperating with said cover means and said container for permitting the swinging of said cover means on said container; cam means on said rack for closing said cover means as said container is being inserted in said rack; and flanges on said cover means extending over said apertures, for preventing dripping liquid from entering said apertures, and spaced from said container for permitting gases to escape from said container through said apertures.

from said container for permitting gases to escape from said container through said apertures.

8. A fireproof container, as for storing such combustible and explosive articles as films and the like, comprising: a fireproof container provided with apertures along its sides for permitting the escape of gases therefrom; a cover means for said container; holding means on said cover and said container and means cooperating with both of said holding means for holding said cover in predetermined positions over said container; and flanges on said cover means extending over said apertures for preventing dripping liquid from entering said apertures, and spaced from said container for permitting gases to escape from said container through said apertures.

9. A fireproof filing cabinet, as for storing such combustible and explosive articles as films and the like, comprising: a fireproof container provided with apertures along its sides for permitting the escape of gases therefrom; a rack for supporting said container and permitting it to slide thereon; a support bar mounted on said container and adapted to cooperate with the front of said rack for holding said container in fixed predetermined advance position substantially out of said rack; a cover means for said container; hinge means cooperating with said cover means and said container for permitting the vertical swinging of said cover means on said container including means for holding it in predetermined positions over said container; cam means on said rack for closing said cover means as said container is being inserted in said rack; and flanges on the said cover means extending over said apertures, for preventing dripping liquid from entering said apertures, and spaced from said container for permitting gases to escape from said container through said apertures.

10. A fireproof filing cabinet, as for storing such combustible and explosive articles as films and the like, comprising: a fireproof container provided with apertures along its sides for permitting the escape of gases therefrom; a rack for supporting said container and permitting said container to slide therewith; a support bar mounted on said container adapted to cooperate with said rack for supporting said container in predetermined tilted position substantially out of said rack; a cover means for said container; a clip on said cover; a corrugated clip on said container, a loop for operating both said clips for holding said cover in adjustable fixed tilted positions over said container; cam means on said rack for closing said cover means as said container is being inserted in said rack; and flanges on said cover means
